UNITED STATES PATENT OFFICE.

WILLIAM W. WHITCOMB, OF BOSTON, MASSACHUSETTS.

SHOWER-BATH APPARATUS.

SPECIFICATION forming part of Letters Patent No. 550,665, dated December 3, 1895.

Application filed January 9, 1895. Serial No. 534,344. (No model.)

To all whom it may concern:

Be it known that I, WILLIAM W. WHITCOMB, residing in Boston, county of Suffolk, and State of Massachusetts, have invented an Improvement in Shower-Bath Apparatus, of which the following description, in connection with the accompanying drawings, is a specification, like letters and numerals on the drawings representing like parts.

10 This invention relates to a novel apparatus to be used by persons in taking a shower-bath. As now commonly practiced shower-baths are taken by a person standing under an apparatus by which the water is sprayed or 15 sprinkled over the person.

The shower-bath apparatus as commonly constructed and known to me is a stationary or fixed apparatus located at a sufficient height above the person to enable the latter 20 to stand beneath the same while the water is being showered or sprayed upon him or her. Such a shower-bath apparatus, while well adapted for the use of the male sex, is not suitable for use by the female sex on account 25 of the disagreeable feature of wetting the head. Owing to the long time required to dry the hair of a woman when wetted, the use of the shower-bath for women is practically prohibited.

30 My present invention has for its object to provide a shower-bath apparatus which is equally well adapted for use by women as by men, as it can be used without wetting the hair or head of the person.

35 In accordance with this invention the apparatus consists of a suitable chamber, the walls of which may be made of rubber, metal, or other suitable material, the said chamber being provided with a water-inlet and with a

40 substantially large number of minute or small openings or perforations on its under surface through which the water admitted into the chamber may find an outlet in the form of a spray or shower. The chamber referred to is 45 provided with a substantially central opening, into and preferably through which the head of the person may pass, and this opening may be round, elliptical, or of other shape. For the best results I prefer that the under side of

50 the chamber should be inclined upward, as will be described, so that the minute streams of water issuing from the perforations or

holes in the under side of the chamber may project toward the body of the person taking the bath. The apparatus may be made as a 55 closed structure and the substantially central opening of sufficient size to enable the apparatus to be placed upon the shoulders or body over the head; or the apparatus may be divided after the manner of a divided ring, so 60 that the ends may be spread apart and passed about the neck of the person. The apparatus may be provided with one or more water-inlets, as will be described. These and other features of this invention will be pointed out 65 in the claim at the end of this specification.

Figure 1 is a plan view, partially broken out, of a shower-bath apparatus embodying this invention; Fig. 2, a central longitudinal section of the apparatus shown in Fig. 1 on 70 the line 2 2; and Fig. 3, a plan view, partially broken out, of a modified form of apparatus to be referred to.

The shower-bath apparatus herein shown as embodying this invention consists of a ring-like structure forming a water-receiving chamber *a*, approximating in form an elliptical ring having a central opening *a'*, the walls of the chamber *a* in the present illustration of this invention being represented as consisting of a substantially flat top 2, the inner wall 3, the outer wall 4, preferably made larger than the inner wall 3, and the lower or bottom wall 5, connecting the bottom of the outer wall 4 with the bottom of the inner wall 3. 85 The lower wall 5 may and preferably will be inclined after the manner shown in Fig. 2, and is provided with a substantially large number of holes, openings, or perforations *a''*, through which the water admitted into the 90 chamber *a* may be discharged upon and against the body of the wearer below the head. The chamber *a* has secured to it a water-inlet pipe *b*, which may have connected to it branch pipes *b'* *b''*, preferably provided with 95 cocks or valves *b'''* *b''''*, and which in practice may be connected by rubber or other suitable pipes *b'''* *b''''* to the hot and cold water faucets, respectively, of a bath-tub such as now commonly found in dwellings. 100

From the above description it will be understood that the apparatus is designed to be fitted over the head of the wearer and the same may rest directly on the shoulders; or

the said apparatus may be suspended in a suitable manner, so that it will be supported off from the shoulders but below the head of the person. In this manner it will be seen that a water-bath apparatus embodying this invention may be used by women without wetting the hair, thereby avoiding the disagreeable features attending the taking of a shower-bath by women with an apparatus such as now commonly employed for this purpose. Furthermore, it will be seen that each dwelling-house may be provided with its own shower-bath apparatus, and by constructing the perforated surface inclined after the manner herein shown the water issuing from the perforations may be directed toward a common center, as it were, thereby avoiding splashing or wetting the room and enabling a shower-bath to be taken in the ordinary bath-tub.

The apparatus shown in Figs. 1 and 2 is represented as of a closed construction—that is, one which requires the apparatus to be passed over the head and onto the shoulders; but, if desired, the apparatus may be made after the manner shown in Fig. 3, so that the apparatus may be applied to the body around the neck without passing over the head.

Referring to Fig. 3, the apparatus is shown as divided or split, as at *c*, and the ends of the chamber are closed by the walls *c'* *c''*. The shower-bath apparatus herein shown may be suspended in a fixed position in a suitable manner; but I prefer to leave the same portable.

The walls of the chamber *a* may be made of rubber, and for the best results I prefer to make them; but I do not desire to limit my invention to this particular material, as the walls may be made of other material, such as metal, wood, or a combination of metal and rubber—as, for instance, the lower

perforated wall 5 of the chamber may be made of wire-cloth or like reticulated material and the remaining walls of rubber. 45

As represented in Fig. 1, the water-inlet pipe is provided with branch pipes *b'* *b''*, which may be integral with the pipe *b* after the manner shown in said figure, and which construction is especially adapted for use with a bath-tub having disconnected hot and cold water faucets; but in some instances the branch pipes *b'* *b''* may be dispensed with and the water-inlet *b* alone used, especially when the hot and cold water faucets of the 55 bath-tub are connected to a common outlet, in which case the said common outlet can be connected by a hose or other suitable pipe with the inlet *b* or when but a single faucet is used. Furthermore, if desired, the apparatus may have attached to it a bonnet, hood, strips, or pieces, which can be fitted on or over the head to suspend the apparatus and also, if desired, to more fully protect the hair.

The gist of this invention consists in providing a suitable structure which will enable a person to take a shower-bath without wetting the hair. 65

I claim—

A shower bath apparatus consisting of an 70 elliptical ring-shaped chamber having the substantially flat top wall 2, the inner wall 3, the outer wall 4 larger than the inner wall 3 and the upwardly inclined bottom wall 5 connecting the walls 3, 4, and provided with a 75 plurality of perforations or openings *a'*, substantially as described.

In testimony whereof I have signed my name to this specification in the presence of two subscribing witnesses.

WILLIAM W. WHITCOMB.
